UNITED STATES PATENT OFFICE.

MYRON H. DISBROW, OF ROCHESTER, NEW YORK.

FRUIT-CRATE.

SPECIFICATION forming part of Letters Patent No. 289,754, dated December 4, 1882.

Application filed February 27, 1878.

To all whom it may concern:

Be it known that I, MYRON H. DISBROW, of Rochester, Monroe county, New York, have invented a certain new and useful Improvement 5 in Fruit-Crates; and I do hereby declare that the following is a full, clear, and exact description of the same, reference being had to the accompanying drawings, in which—

Figure 1 is a perspective view of the device. Fig. 2 is a view of one of the sectional frames. Fig. 3 is a detail view.

My improvement relates to crates for conveying berries and other fruits in baskets or packages placed within the crates; and it consists of a crate composed of separate sections, each made of four strips of wood fastened together at the ends in square or rectangular form, the said sections being placed at proper distance apart and secured by thin angular 15 corner-pieces of metal nailed thereto, as hereinafter described.

In the drawings, A A represent a series of the rectangular frames in crate form. Each one of these sections is made of four thin and narrow strips of wood or veneer, two forming the sides and two the ends. The ends of these strips are dovetailed or otherwise fastened together, forming the complete frame.

B B are the metallic corner-pieces, of which 30 one is used at each corner of the crate. Their length is the height of the crate, and in cross-section they are of right-angled form, one flange lapping the side and one the end of the crate.

To make the crate, the separate sections before described are placed upon a form at the right distance apart to form the ventilating spaces or cracks, the corner pieces are placed

upon the corners overlapping the frames, and 40 nails or screws are then driven into the wood through holes in the corner-pieces. A closed bottom is secured to the lower sectional frame, and a cover is hinged or otherwise attached to the top one.

The crate thus constructed of separate frame-sections and metallic corner-pieces connecting the sections, is peculiarly adapted to berry-crates, as they are thin, light, there is no projection in the interior space as where posts are used, therefore the baskets can fill to the ends 45 as well as the sides, and furthermore, in building the crates the sections can be placed nearer together or farther apart with great facility 50 and ease, thereby adapting the crate to the size of the baskets, so that the division-boards 55 between the layers of baskets shall come opposite to or in conjunction with the closed sides of the frames.

The crate is much thinner and lighter than common crates where slats are nailed to posts, 60 and can be made at small expense.

Having thus described my invention, I do not claim, broadly, a slatted crate nor metallic corner-pieces; but

I claim—

A fruit-crate, as a new article of manufacture, embracing the combination of a series of rectangular frames and angle-irons, the frames being sustained at their corners and at definite distances from each other by the angle- 70 irons, as hereinbefore set forth.

MYRON H. DISBROW.
